To all whom it may concern:

Be it known that I, JOHN W. MEALY, a citizen of the United States, residing at Baltimore, in the State of Maryland, have invented and produced a new and original Design for a Badge or Similar Article, of which the following is a specification.

The leading or material feature of my design consists of a body having an approximately shield-shaped outline with two circles thereon, one within the other, a triangle within the inner or smaller circle, and a represen-

tation of the sun's rays on each of the three sides of the triangle, as shown in the accompanying drawing.

Having thus described my invention, what I claim as new, and desire to secure by Letters Patent, is—
